moisture barrier. In order to combat further the moisture absorption problem, the entire assembly as shown in Fig. 5 may be dipped or otherwise covered with a protective coating such as one of the more suitable synthetic resinous materials.

In use of the invention, external circuitry is connected with the circuit connection wiring 22 and 24, solder in areas 18 and 20, the clamps 30 and 32 and finally the capacitor 12 through its electrodes 14 and 16. Accordingly, two conditions must exist for the capacitor to be satisfactorily operative. There must be a firm mechanical connection between clamps 30 and 32 and the capacitor electrodes 14 and 16. The reason for this is that there should be no motion of the capacitor 12 with respect to its supporting base 10. To aid in this regard, a quantity of cement may be applied to the capacitor 12 or to the base 10 so that when the capacitor 12 is seated on base 10 between the clamps 30 and 32, the cement holds it, coacting with clamps 30 and 32 for final, secure attachment. The second important reason why there must be firm connection between the capacitor electrodes and clamps is one of electrical continuity. Inspection of Fig. 3 shows clearly that the clamps 30 and 32 are an intermediate part in the circuit. As an aid in both mechanical connection and electrical continuity various expedients may be resorted to. One is illustrated in Fig. 4, where a quantity of cement 40 is shown to be present in the clamp 30. This cement contains conductive metal particles, as aluminum, and the cement aids in holding the capacitor 12 firmly in place.

Many modifications may be made without departing from the inventive concept. The invention is not to be deemed as limited except within the scope of the appended claims.

What is claimed is:

1. In a capacitor assembly, a base of flat rigid insulating material having notches in the edges thereof, spaced

parallel elongated solder areas on said base, metallic conductors on said base leading between their respective solder areas and notches, a wound capacitor having aluminum foil electrodes projecting from opposite ends thereof, and elongated metallic clamps of channel section in soldered engagement with their respective solder areas, each clamp having parallel opposed leg portions in clamping engagement with its respective electrode, said leg portions each having a length substantially corresponding to the width of said electrodes.

2. In a capacitor assembly, a base of flat rigid insulating material having notches in the edges thereof, spaced parallel elongated solder areas on said base, metallic conductors on said base leading between their respective solder areas and notches, a wound capacitor having foil electrodes projecting from opposite ends thereof, and elongated metallic clamps of channel section in soldered engagement with their respective solder areas, each clamp having parallel opposed leg portions in clamping engagement with its respective electrode, said leg portions each having a length substantially corresponding to the width of said electrodes, said capacitor being of greater width than thickness and having flat surfaces on opposite sides thereof, with one of said surfaces in flush engagement with 25 said base.
